GRINDING MACHINE

Charles V. Walter, Bronxville, N. Y.

Application March 10, 1931, Serial No. 521,462

27 Claims. (Cl. 51—124)

This invention relates to grinding machines, and more particularly to machines for beveling and finishing off the edges of watch glasses or disks of glass or other material.

5 In the preferred embodiment of my invention, the beveling of the disk is accomplished by holding and rotating the disk with its edge in contact with an approximately flat grinding surface of annular shape, which forms a part of a rotary grinding wheel. Suitable means are provided for holding the disk at the proper angle to the grinding surface to give the required angle of bevel, and this holding means not only rotates the disk about the axis of the disk but also moves 10 or swings it in a direction toward the center of the grinding wheel so that the entire width of annular grinding surface is traversed during the operation.

The grinding wheel also carries a second grinding surface inside of and concentric to the above mentioned surface and the swinging movement of the disk holder, after carrying the disk inwardly over the first mentioned surface, carries it on to the second surface, which, in the preferred embodiment of my invention, is a strip of felt which serves to polish the beveled edge of the disk.

If desired, also, I may provide the face of the grinding wheel with three or more concentric, 30 annular grinding surfaces of different degrees of fineness which act successively on the disk to produce rough and fine grinding and polishing. After passing over the successive grinding or polishing surfaces, the beveled disk then preferably passes along the surface of a second grinding wheel, which has the effect of taking off the sharp edge or acute angle of the bevel. The particular arrangement of the two grinding wheels for accomplishing the results above described is 35 one of the features of the present invention and will be described in detail hereafter.

Also, in the preferred embodiment of the grinding machine herein disclosed, I have provided means by which the disk holder automatically receives the disk to be beveled and on completion of the beveling and finishing operations, automatically discharges the disk to a suitable receiving apparatus, such as a conveyer. The machine arrangement illustrated comprises what 40 may be termed a receiving or pick-up station at which the disk is received by the holder and a discharge station, at which the finished disk is discharged. These two stations are located at different points about the axis of the grinding 45 wheel and the disk holder, during the grinding

operation, is moved around the axis of the grinding wheel from the receiving to the discharge station, the disk holder thus having a planetary motion with respect to the axis of the grinding wheel.

5 In practice, I employ a plurality of disk holders all concurrently cooperating with the grinding wheel. These several holders are located at equally spaced points around the grinding wheel and all move simultaneously around the axis of 10 the wheel, thus passing successively by the receiving station, traveling around the grinding wheel, and passing successively by the discharge station, the arrangement being such that the disks held by a number of successive holders will 15 be undergoing successive stages of grinding, while another holder will be receiving a new disk, and yet another holder will be discharging a disk which has been ground.

In practice, I employ air suction for holding 20 the disk to the holder, and my invention contemplates, among other features, the provision of an improved air system whereby the air pressure at the several disk holders may be automatically controlled for releasing and applying 25 the suction, for discharging and receiving of disks, respectively. Also, I provide the air system with improved automatic cut-offs designed to relieve the suction from any disk holder in case the disk or lens held thereby is broken, or if, 30 for any other reason, the disk does not make a proper sealing contact with the holder, as will be more fully described and explained hereafter.

At the receiving station, I preferably employ a suction operated pick-up device which automatically picks up the disks to be ground from a stack of disks, and transfers each disk to the disk holder of the grinding machine while the latter is moving toward its initial grinding position. In certain cases it may be desired to have 40 a disk operated upon by a plurality of grinding machines, and in this event a suction pick-up device of described character may be employed to transfer the disk from one machine to another.

From the above brief description it will be seen 45 that I provide a disk beveling machine which is entirely automatic in operation, which is designed to operate on a plurality of disks simultaneously, and wherein each disk is subject automatically to a series of grinding and finishing operations.

50 The machine disclosed in the accompanying drawings embodies numerous improvements in its various parts, among which are: an improved means for insuring a constant angle of bevel of the disks; means for insuring that the disks shall,

if desired, be ground to one bevel and to one outside diameter; adjusting means for changing the angle of bevel and diameter, as desired; means for adjusting the grinding wheel to compensate for wear of the abrasive material, which adjustment may be automatic or hand operated, as desired; an improved means for maintaining the moving parts oiled particularly in conjunction with an air system wherein danger of sucking oil into the air system is eliminated.

Among the other objects of my invention is the provision of a machine of the character described, which is relatively simple in construction, strong and durable in operation, which does not require the exercise of high technical skill for its operation, and which requires the minimum attention of the operator.

Numerous other objects and advantages of my invention will appear from the following description taken in connection with the accompanying drawings, wherein:

Figure 1 is a side elevation of a grinding machine embodying one form of my invention, certain of the parts being omitted for the sake of clearness,

Figure 2 is a side elevation, looking from the right of Figure 1, the disk holder head being omitted,

Figure 3 is a top plan view of the machine, showing the disk holders arranged around the main grinding wheel, and showing, also, a portion of the pick-up mechanism,

Figure 4 is a central, vertical, sectional view taken on the line 4—4 of Figure 3, certain of the parts being broken away and others being shown in elevation,

Figure 5 is a diagrammatic plan view of the grinding wheel and the disk holders, showing successive positions of the holders in their progress from the receiving to the discharging stations.

Figure 6 is an enlarged, detail view, showing a disk held against the main grinding wheel in the operation of forming the bevel on the disk,

Figure 7 is a view similar to Figure 6, but showing the disk in contact with a second grinding wheel which serves to cut off the sharp edge or angle of the bevel, and showing the stopping means for the disk-holder frame which serves to hold the disk in positive engagement with the cutting wheel.

Figure 8 is a similar view, but showing the disk raised from the outer grinding surfaces of the main wheel, this occurring after completion of the grinding operation and while the disk is being moved outwardly over the other grinding surface toward the discharging station,

Figure 9 is a view still further enlarged, of the disk in contact with the grinding wheel, showing how the relative arrangement of grinding surfaces on the main and auxiliary grinding wheels serve to shape the edge of the disk,

Figure 10 is a horizontal, sectional detail view, taken on the line 10—10 of Figure 1, certain of the parts being shown in elevation,

Figure 11 is a vertical sectional detail view, taken on the line 11—11 of Figure 10, and showing part of the gearing used for adjusting the height of the main grinding wheel,

Figure 12 is a view similar to Figure 11, but taken on line 12—12 of Figure 10, and showing a part of the driving means for giving to the disk-holder heads a planetary movement around the axis of the main grinding wheel.

Figure 13 is a fragmentary, vertical, sectional

view, taken on the line 13—13 of Figure 3, and showing a portion of the main grinding wheel and, in addition, the auxiliary grinding wheel in grinding contact with the edge of the disk, together with the mounting for the auxiliary wheel, 5

Figure 14 is an enlarged fragmentary sectional view similar to Figure 4, showing portions of the grinding machine and pick-up mechanism, with certain of the operating parts in section,

Figure 15 is a diagrammatic view of the cam 10 used for operating the clutch shown in Figure 14, which is connected between the source of power and the gearing for rotating the disk about its own axis while the disk is in contact with the grinding wheel.

Figure 16 is a vertical sectional view through a disk holder head or assembly showing disk-holder nozzles of the grinding machine and pick-up mechanism holding a disk between them in the act of transferring the disk from the pick-up nozzle to a disk-holder nozzle of the grinding machine.

Figure 17 is a sectional view taken on the line 17—17 of Figure 16, and showing part of the transmission mechanism employed for rotating 25 the disk about its own axis,

Figure 18 is a vertical sectional view taken on the line 18—18 of Figure 16, showing a portion of the air suction passage from the disk holder nozzle.

Figure 19 is a detail vertical sectional view, taken on the line 19—19 of Figure 16, and showing the actuating cam for raising the disk off from the grinding wheel after completion of the grinding operation as it is moved outwardly to- 35 toward the discharge station,

Figure 20 is a horizontal sectional view, partly broken away, taken on the line 20—20 of Figure 4, and showing the segments employed for rotating the disk-holder heads or assemblies about 40 their vertical axes so as to swing the disk inwardly and outwardly across the grinding surfaces,

Figure 21 is a sectional view, taken on the line 21—21 of Figure 3 and showing parts of the pick- 45 up mechanism in elevation,

Figure 22 is a detailed view of the means for lifting a stack of disks toward the pick-up nozzle in order that the nozzle may pick up the top disk of the stack for transfer to the disk holder 50 of the grinding machine,

Figure 23 is a diagrammatic view, showing the grinding machine disk holder and pick-up nozzles in their relative positions prior to the transfer of the disk from the pick up to the grinding nozzle 55

Figures 24, 25, and 26 are views of the structure shown in Figure 23, but showing the parts in the positions which they occupy successively in transferring the disk from the pick up to the grinding machine nozzle,

Figure 27 is a detail horizontal sectional view, taken on the line 27—27 of Figure 4, and showing a portion of the suction air passage of a disk holder assembly, including part of a control valve for applying and removing the suction as the disk is respectively received by the disk holder nozzle, and subsequently discharged after the grinding operation; and also showing a portion of the automatic cut-off valve for relieving the disk holder of suction when a defective lens is received by 70 the nozzle,

Figure 28 is a vertical sectional view taken on the line 28—28 of Figure 27,

Figure 29 is a side elevation of the structure shown in Figure 28, looking from the right and 75

showing the operating means for the control valve.

Figure 30 is a view similar to Figure 29, but showing the control valve in a different position,

5 Figure 31 is a perspective view of parts of the control valve, separated from one another to show the internal air passages,

10 Figure 32 is a sectional view on the line 32-32 of Figure 27, showing the automatic cut-off valve and passages leading thereto,

15 Figure 33 is a detail horizontal sectional view, taken on the line 33-33 of Figure 4, and showing the stationary lugs against which the control valve actuator impinges in the act of cutting off and applying the suction,

20 Figure 34 is similar to Figure 29, but shows the relative position of the parts prior to cutting off the suction,

25 Figure 35 is a diagrammatic view, showing the suction passages from the pick up nozzle to the valve for controlling the pick up suction, together with the cam actuated operating means for the pick up control valve,

30 Figure 36 is a sectional view on the line 36-36 of Figure 35, showing the automatic cut off valve for the pick up nozzle,

35 Figure 37 is a sectional view, taken on the line 37-37 of Figure 35, and showing a portion of the suction passage through the control valve for the pick up nozzle,

40 Figure 38 is a sectional view on the line 38-38 of Figure 35, showing the means for holding the air coupling at the end of the pick-up nozzle shaft from rotating while at the same time permitting the shaft to be moved longitudinally.

45 Figure 39 is a side elevation showing the modification of the actuating means for adjusting the height of the main grinding stone.

50 Figure 40 is an elevation of the structure shown in Figure 39, viewed from the right; and Figures 41 and 42 are diagrammatic views for transferring a disk from one grinding mechanism to another.

55 Referring to Figures 1 to 4, the grinding machine A comprises a wheel B adapted to be rotated by means of a shaft C' in a horizontal plane. Mounted at the outer edge of the wheel B is an annular grinding stone C, and also mounted on the wheel B and located inside of the stone C is an annular strip of felt D, this strip being positioned in substantially the plane of the upper surface of the stone C. Located above and eccentric to the axis of grinding wheel B is a second grinding wheel F which has a lower annular grinding surface G, shown more clearly in Figure 13. Wheel F is carried by a vertical shaft H, shown in Figure 13.

60 Adapted to revolve around the axis of the grinding wheel B is a turn table J, upon which are mounted a plurality of disk holder heads or assemblies, ten in number and indicated generally by the reference character K. These disk holder assemblies each comprise a suction disk holder L, which is carried by a frame M, mounted to rotate slightly about a horizontal pivotal axis N, shown more clearly in Figure 14. The disk O, which may be a watch glass, shown, for example, in Figure 14, is held by suction against a seat P of the disk holder.

65 70 It will be noted that due to the location of the pivotal point of the frame M, rotation or tilting of the frame M will cause the glass disk O, carried by the disk holder, to be raised and lowered with very little change of the angle of the disk to the vertical.

The frame M is mounted on a supporting structure Q, which, in turn, is rotatably mounted on the turn table J so as to swing about a vertical axis Q', the construction and arrangement being such that rotation of the structure Q serves to 5 swing the disk holder in a horizontal plane, swinging the disk toward or away from the axis of the main grinding wheel B.

Reference character R represents gearing mounted partly in the frame M and partly in the 10 supporting structure Q. This gearing is designed to be operated by a vertical shaft S, whose axis is coincident with the axis Q' of the structure Q. Gearing R serves to rotate the disk O about its own axis, as will be more fully explained here- 15 after.

From the above brief description it will be apparent that the disk O is supported in such a manner that it may be rotated about its own axis through the gearing R, and that, by reason 20 of the pivotal connection at N, between the frame M and supporting structure Q, the disk also may be raised and lowered. Furthermore, by reason of the rotatable mounting of the structure Q on the turn table J, the disk may be swung to 25 ward or away from the axis of the main grinding wheel, and also by reason of the rotatable character of the turn table J the disk O, with the entire disk holder assembly, may be rotated completely around the axis of the grinding 30 wheel B.

In the grinding machine shown in the drawings there are illustrated means for imparting to the disk all of the motions above described, and in Figures 5 to 9, inclusive, I illustrate motions 35 of the disk during the complete cycle of operations, by indicating different positions of the disk holder and disk. The position of the holder and disk about the axis Q' as the turn table J is rotated are shown in Figure 5 and indicated 40 by the reference characters P1 to P16, inclusive.

At the position P1 the disk is at the receiving station, where the disk holder has just received its disk from the nozzle X of a pick-up mechanism, designated generally by the reference 45 character T in Figures 3 and 4.

In this position the disk holder extends outwardly in a substantially radial plane from the axis of the wheel B in the position shown, for example, in Figure 4.

50 The turn table, as well as the wheel B are indicated in Figure 5, as rotating in a clock-wise direction. Rotation of the turn table serves to move the axis Q' of the shaft S, which is the axis about which the structure Q rotates on the turn table downwardly and toward the left from the position P in Figure 5. Simultaneously the structure Q is turned about this axis so as to swing the disk holder to the position P2, where the disk O is about to engage the upper surface of 60 the grinding stone C. The angle between the disk and the stone is approximately 60°, as shown, for example, in Figure 9. It will be understood, however, that by suitable adjustment of the parts this angle may be changed as desired. Further operation of the parts moves the disk holder to the position P3, in which it will be seen that the edge of the disk O has travelled partly over the width of the annular grinding stone C, the lower edge of the disk, during this motion, remaining in grinding contact with the top of the stone, and because of rotation of the disk about its own axis by the gearing R, the disk is ground around its entire edge at an incline, as indicated 65 in Figure 9.

At P4, P5, and P6, I show subsequent positions of the disk and disk holder from which it appears that, as the turn-table rotates, the disk moves inwardly across the grinding stone C.

5 In position P7 the grinding of the disk is complete and the disk is moved inwardly on to the annular strip of polishing felt D.

In the position P8 the disk is shown as having moved partly across the felt, the felt serving to 10 polish the ground bevel surface.

In position P9 the disk is moved inwardly entirely across the strip of felt D and is about to move under the second grinding wheel F.

In Figures 7, 9, and 13 I show the disk in engagement with the lower annular grinding surface G of the wheel F, this being substantially 15 the position of the disk at P10 in Figure 5.

During the passage of the disk from position P3 to P8, the weight of the disk holder and the 20 frame M, acting about the pivotal point N of the frame M, has served to press the disk at its edge against the grinding and polishing surfaces of the wheel B. As the disk passes inwardly off from the felt strip to position P9, the frame M, 25 disk holder, and disk swing downward by gravity a short distance, this downward motion being halted by a device, indicated by the reference character U, in Figure 7, which determines the elevation of the axis of the disk as it moves under 30 the second grinding wheel F.

The second grinding wheel F is vertically adjustable and is so positioned with respect to the center of the disk O that it serves to cut off the sharp angle at one edge of the bevel.

35 It will be noted, also, from an inspection of Figure 9 that the action of the wheel F serves to reduce the diameter of the disk somewhat and the vertical adjustment of the grinding wheel F and the device U is such as to give the finished 40 disk the required diameter.

In position P11 the disk is shown as it is about to pass from under the grinding wheel F, and it will be noted that at this time the disk 45 holder is approximately radial to the axis of the grinding wheel B.

Immediately after passing from position P11, the supporting structure Q is rotated with respect to the turn table J so as to turn the disk holder toward the position P12, from which it will be 50 seen that the disk is now being carried outwardly with respect to the axis of grinding wheel B. This turning movement causes the disk to move back onto the felt D and after the disk has traversed the felt a second time, the device U, which 55 serves as a stop to the downward swinging movement of the frame M, operates to swing this frame upwardly into a position shown diagrammatically in Figure 8, thus raising the disk O above the level of the grinding surface. Thus 60 the disk in moving outward does not contact with the surface C.

P13, P14, and P15 show subsequent positions of the disk holder, the holder continuing its outward rotation until, in the position P16, the holder extends radially outward from the axis of the wheel B.

The disk is now at the discharge station, and suitable means, to be described hereafter, operates at this point to relieve the disk holder nozzle of suction so that the disk drops from the holder onto an appropriate receiving device, such as a travelling carrier W, shown diagrammatically in Figure 5.

Between position P16 and P1, the holder 75 operates with the pick-up mechanism T, in a

manner which will be described more fully in detail, to receive a new disk to be ground.

Grinding wheels, drive, and adjustment

The main grinding wheel B comprises two 5 castings,—one, a casting 10, having a central hub portion 11, secured to the upper end of the vertical shaft C', and an outer portion 15, having an annular socket 16, designed to hold the grinding stone C, (see Figure 4). Between the hub 10 11 and the outer portion 15, the casting 10 forms an intermediate chamber, or space 17, in which is located the second casting 19. The upper portion of the hub 11 is screw-threaded, as indicated at 20, so as to permit the casting 19 to be 15 screwed on to hub portion of the casting 10. The two castings are rigidly secured to one another by a screw device 22, consisting of a tapered key 24, fitting a slot in the threaded hub 11, and engaging outwardly against the wall 24' of a slot 20 in the casting 19. The key 24 is pressed downwardly so as to engage tightly in the slots by means of a bolt 26, threaded through the key and into the casting 19, thus holding the casting 19 against rotation on the hub 11. 25

At the outer edge of the casting 19 is secured, by means of bolts 30, an annular bed plate 31, formed with a seat for receiving the annular strip of felt D. It will be seen from Figure 4 that the outer edge of the casting 19 and felt D are 30 spaced somewhat from the inner face of the stone C, thus permitting the water supplied to the stone C, during the grinding operation, to flow between the stone and felt into the chamber 17, from which it finds its exit through one or more 35 openings 32 in the outer face of the casting 19.

From the openings 32 the water flows into an annular trough 35 formed in the turn table J, and from this trough flows through one or more tubes 36, into a second annular trough 37, formed 40 in a stationary casting 38, rigidly secured to a column casting 39, forming part of the stationary frame of the machine.

The trough 37 communicates by means of a bore 41 with a passage 42 in the casting 39 and 45 passage 42, in turn communicates with a pipe, or other conduit 44, from which the water may be discharged into a suitable drain.

It will be seen that castings 10 and 19 are connected to one another in such a way that the 50 casting 19 may be raised and lowered with respect to the casting 10 by removing the locking device 22 and turning the casting 19 on the hub 11, and in this manner the elevation of the felt 10 with respect to the stone C may be adjusted. When 55 grinding surfaces are employed of different material which wear down at different rates, this relative adjustment may be employed to maintain the grinding surfaces at substantially the same level. 60

The main grinding wheel formed by the castings 10 and 19 may be adjusted vertically with respect to the turn table J, upon which are mounted the central disk holders. For this purpose I provide a vertically movable and non-rotatable sleeve 50, which surrounds the shaft C', and serves to support the rotating grinding wheel through a ball-bearing 51 between the upper end of the sleeve 50 and a shoulder 52 of the shaft C', (see Figure 4). The sleeve 50 is keyed to a 70 slide in the stationary column 39, and is adapted to be raised and lowered by an internal screw-threaded gear 54 which engages external screw-threads formed at the bottom of the sleeve 50. 75

Gear 54 is held against a vertical movement be- 75

tween the casting 39 and a casting or bolster plate 56, forming part of the stationary structure of the machine and supported by feet 68 from the base 69. Gear 54 is mounted to rotate in ball bearings 57 in a central portion of the bolster casting 56. The gear 54 is rotated by means of a spur gear 58, shown in Figure 11, which engages the outer teeth 59 of the gear 54. Spur gear 58 is secured to a vertical shaft which carries at its lower end a worm gear 60 operated by a worm 61 secured to a horizontal shaft 62 which extends outwardly through a side wall of the bolster plate, as shown in Figures 2 and 10, to a hand wheel 66. By turning the hand wheel 66, the gearing 62, 60, 58, 54 is operated, and the elevation of the grinding wheel B adjusted.

Vertical adjustment of the grinding wheel B may be necessary to take up for wear of the grinding stone C, also in certain machines for changing the angle of bevel, or changing the vertical distance between wheels B and F. In this connection it is to be noted that the final diameter of the disk is determined by the elevation of the wheel F and adjustment of the devices U, each of these devices being independently adjustable to limit the elevation of the disk as it passes under the grinding wheel F. By making the devices U independently adjustable, in a manner to be explained hereafter, it is possible to so adjust the final diameter of each disk that all disks delivered by the machine will be of uniform diameter.

In Figures 39 and 40 I show means for automatically and periodically raising the wheel B to compensate for wear of the abrasive material. This means comprises a ratchet wheel 70 secured to the shaft 62 and designed to be rotated by a pawl device 71 having an actuating rod 71' mounted to slide in brackets 72 secured to the frame of the machine. Rod 71' is normally held in raised position by a spring 72' and is adapted to be periodically depressed by a lug 73 carried by a slowly rotating part 242 of the grinding machine. The particular construction of the part 242 and the manner in which it is rotated will be described more fully hereafter. Depression of the rod 71' by the lug 73 serves to rotate the ratchet wheel 70 a fraction of a revolution and in this manner slowly raises the grinding wheel B. Connecting link 73' between lug 73 and rod 71' is preferably pivoted so that it can be swung out of the way when it is desired to discontinue the automatic adjustment of wheel B.

Power for driving the various parts of the machine is derived from an electric motor 75 on the shaft of which is a pinion 76 which drives a gear 78 mounted at one end of a shaft 79 shown in Figures 2 and 10. Shaft 79 is mounted in suitable bearings, as shown, and extends beneath the machine to a change speed gearing, shown conveniently at 80, which drives the turn table J and pick-up mechanism T, as will be described more particularly hereafter. Keyed to the shaft 79, intermediate its length, is a beveled gear 84 which meshes with a gear 85 mounted on a vertical shaft 86, shown at the left of Figure 4.

Rigidly secured to the beveled gear 85 is a gear 90 which drives a gear 91 secured at the bottom of the drive-shaft C'.

It will thus be seen that the main grinding wheel B is driven from the motor 75 through pinion 76 gear 78 shaft 79 beveled gears 84 and 85 gear 90 gear 91 and shaft C'.

The motor 75 may, if desired, be provided with suitable controlling means for changing its speed.

The frame of the machine comprises pedestals

69' carrying brackets 77 and terminating in supporting columns 92 connected at their upper ends by a channel bar 93, (see, particularly, Figure 2). The channel bar is formed, or has secured thereto, between its ends, a downwardly inclined guideway 93' having a dove-tailed channel 93'' in which is slidably and adjustably mounted the bearing supporting member 94 for the shaft H of the grinding wheel F. The shaft H extends vertically through the member 94 and is journaled in ball bearings 94' in the member 94.

The inner wall of the channel 93'' is formed with elongated slots through which project bolts 95 secured to the member 94. By loosening the bolts 95 the wheel F may be adjusted toward or away from the grinding wheel. Adjusting movement of the wheel F is preferably accomplished by a hand-wheel 96 secured to a shaft 96' screw threaded into the top of guideway structure 93'. The bearing supporting member 94 is formed with a bracket 94'' which surrounds, and is seated in a groove, in, the shaft 96' so that when the shaft 96' is screwed into or out of the structure 93' the bearing supporting structure 94 is moved down or up along the dove tail channel 93'.

As may be seen from Figure 13, the grinding wheel F has a relatively narrow annular grinding surface G and from Figure 2 it will be seen that adjustment of the wheel F away from the wheel B has the effect of moving the wheel F toward the center of the wheel B. This is to insure a correct positioning of the wheel F for disks of different diameters. For example, by reference to Figure 13 it will be seen that with the disk holder in the position shown but with a larger disk held by the holder, an adjustment of wheel F upwardly and also away from the disk holder is necessary, in order that the upper edge of the disk will be cut off by the correct amount, and in order that this upper edge will engage approximately the same part of the grinding surface of wheel F.

Shaft H, which carries the wheel F, has secured thereto, near its upper end, a pulley 98 adapted to be engaged by a belt 99 driven from a suitable source of power, such as the motor 75 by any suitable transmission, not shown.

The turn table, disk holder assemblies, adjustment and drives

The change speed gearing 80 may be of any conventional type and serves to drive at the desired speed a horizontal shaft 100, which, as shown in Figures 2 and 10, is located directly above the main driving shaft 79. Secured to the inner end of shaft 100 is a worm 101 which meshes with and drives a worm wheel 102 mounted on a vertical shaft 103. Shaft 103 carries two gear wheels, a beveled gear 104 mounted at the bottom of the shaft which serves to drive a horizontal shaft 108 which, in turn, drives the pick-up device, (see, particularly, Figure 10), and a second gear 110 secured to the upper end of the shaft 103 and meshing with an internal gear 112 rigid with the turn table J, (see, particularly, Figure 12).

As shown in Figure 4, the gear 112 is in the form of a ring bolted to the lower face of a portion 115 projecting outwardly from the hub portion 116 of the turn table J.

In practice, the turn table rotates in the same direction as the grinding wheel B, as indicated, for example, by the arrows in Figure 5, but at a very much slower speed. Inasmuch as one complete rotation of the turn table carries the disk through the entire cycle of grinding and finish-

ing operations, the speed of the turn table is so adjusted that the disk will be maintained in contact with the grinding surfaces the requisite length of time for properly completing the grinding operation.

The turn table J, which is preferably formed of aluminum, has its outer and upper surface 130 machined or ground to a plane, (see Figures 14 and 16). This portion of the turn table is formed with a series of equally placed openings 131 which, in the present instance, are ten in number and held in each of the openings 131 is a bushing 132 of bronze or similar bearing metal, having an upper horizontal flange 134 extending over and in facial contact with the surface 130 of the turn table casting.

Journaled in the bushing 132 and extending above and below the bushing is a tubular shaft or sleeve 136 which is held against upward movement through the bushing by a collar 137 suitably secured to the sleeve 136.

Secured to the upper end of the sleeve 136 is the supporting structure Q which is formed at its bottom with an outwardly extending flange 139, (see Figure 16), which rests in facial contact with the upper face of the bushing 134, the mutually contacting faces of the flange 139 and bushing 134 being ground accurately to a plane so as to insure a sealing contact between these two members and to prevent leakage of air into the suction passages extending through these members. Surrounding the flange 139 of the supporting structure Q is a guard 141 formed with a vertical flange 142 which serves as a protecting means to prevent access of dirt to the bearing surfaces of flange 139 hollow shaft 136 and the bushing 134.

The guard 141, bushing 132, and turntable are rigidly secured to one another as by means of bolts 145, shown, for example, in Figure 16. The supporting structure Q near its base carries a transverse pin or trunnions 147 on the ends of which are pivotally mounted, respectively, the side plates 149 of the supporting frame M. The center line of the trunnions 147 is the axis N about which the frame M tilts. The plates, as shown in Figures 4 and 16, extend down into the guard-flange 142 and are cut away at 151 to form a recess into which the flange 142 projects. The lower edges of the plates 149 outside of the flange 142 are joined by a U-shaped piece of metal 153, shown in section in Figure 16.

The general contour of the side plates 149 is shown in Figures 4 and 14, and also in dotted lines in Figure 16. Rigidly held between the side plates 149 by bolts 155 is the disk-holder L which is tubular in form and comprises an outer casing 160 closed at its outer end by a plug or cap 162 screwed to the casing 160 and having a central opening therethrough, through which projects the rotary shaft 164 of the disk-holder nozzle, (see Figure 16).

The shaft 164 extends the length of the casing 160 and is supported adjacent opposite ends of the casing by ball bearings 167. This shaft has a longitudinal opening 163 therein which forms a suction passage for the nozzle P.

The nozzle seat comprises a metal collar 168, screw-threaded on to the end of the shaft 164 and formed at its lower or outer end with a shoulder 170 upon which is seated the rubber ring 171. The outer end of the collar 168 inside the rubber ring is formed as a cylindrical bead 173, which is highly polished and is adapted to contact with the disk O when the disk is seated on the nozzle.

In practice, particularly when it is desired to form disks of uniform diameter, it is desirable that the disk be held securely at definite distances from other parts of the grinding head, or assembly. By the use, only, of a compressible rubber seat, different lens holders might hold their respective lenses at slightly different positions relative to the other parts of the machine and, to avoid this, I have provided a definitely positioned stop for the disk in the form of an annular bead 173, which may be accurately positioned with respect to other parts of the machine so as to insure a constant, spacial and angular relationship between several disks and the grinding surfaces and thereby insuring a uniform product.

Between the cap 162 and the ball bearing 167, the shaft 164 has secured thereto a collar 172, having an enlarged portion 173, which extends around the seating member 168. Between this portion of the collar 172 and the cap 162, I preferably employ a felt washer 175.

Inwardly from the bearing 167, the shaft 164 is formed with a flange 180 which fits the outer cylindrical casing 160, and between this flange and the bearing 167 is a felt washer 181. Shaft 164 is supported near its opposite end by the bearing 167, and inwardly of this second bearing I provide the shaft 164 with a collar 183 which may be pressed on to the shaft, or otherwise suitably secured thereto. Between the collar 183 and this bearing 167 I also provide a felt washer 184. The upper end of the casing 160 is closed by a screw threaded cap, or plug 186, having a central opening through which the shaft 164 passes. Shaft 164 has secured to the inner end a beveled gear 187, which is seated against a shoulder 188 formed in the cap 186.

The top of the columnar structure Q is formed with upwardly and laterally extending flat projections 190 in which are a journaled transverse shaft 192 shown, for example, in Figures 16, 17, and 19, and a transverse shaft 193, shown in Figures 16 and 17. The shafts 192 and 193 are journaled in ball bearings 196, secured to the outer faces of the extensions 190 by bolts 197.

Rotatably mounted in the side plates 149 is a transverse shaft 198 carrying a beveled gear 199, which meshes with the gear 187 on the nozzle shaft 164. Shaft 198 also carries a spur gear 200, which meshes with a gear wheel 201 secured to the transverse shaft 193. Gear 201 in turn meshes with and is driven by a gear 203 secured to the transverse shaft 192 and transverse shaft 192 has also secured thereto a beveled gear 205 which meshes with a beveled gear 206 secured to the top of the vertical driven shaft S.

As previously stated, the disk holder L and connected frame M are adapted to rock about the pivots 147 and, as shown, for example, in Figures 4, 14, 16, and 17, the side plates 149 are so shaped as to permit a slight rocking movement without obstruction by the shafts 192 and 193.

When the frame M tilts on its axis N the axis of the gear 200, which is secured to the frame M moves in direction substantially tangential to the periphery of the gear 201 secured to the structure Q. As the tilting of the frame about this axis is comparatively slight the relative movement of the gears 200 and 201 is not such as will interfere with the meshing of these gears.

Downward rocking movement of the frame M is stopped by the device U, namely, by engagement of the inner end of an adjustable screw 210 carried by a cross piece 211 secured at its opposite ends to the side plates 149 with the head 75

of a bolt 212 secured into a cross member 214 rigidly secured to the top of the extensions 190 of the supporting structure Q.

Referring again to the disk holder L, the bore or air passage 163 in the rotary shaft 164 of the disk holder terminates midway of the length of the shaft and there communicates with a transverse opening 215 extending to the bottom of an annular groove 216 formed in the outer cylindrical face of the shaft 164. Between the shaft 164 and the inner wall of the cylindrical casing 160, at this point is a cylindrical tube section 218 which is rigidly secured in the casing 160 by a threaded nipple 220 screwed into the casing 160 and the member 218. This nipple and the openings into which it is screwed form a communication between a flexible pipe 221 and the annular recess or groove 216 in the rotary shaft 164.

It will be seen from this construction that suction may be applied to the nozzle through pipe 221, through the nipple 220, recess 216, transverse opening 215, and longitudinal bore 163 of the nozzle shaft. The cylindrical member 218 terminates at one end short of the flange 180 on the shaft 164 and at its opposite end short of a collar 193, thus leaving annular spaces 225 around the shaft 164. These spaces communicate with openings 226, extending through the casing 160. The purpose of this construction and arrangement is to prevent the suction applied from the tube 221 from drawing oil from the bearings 167 into the air suction passages.

The shaft 164 and member 218 are accurately machined to a close running fit so as to minimize the leakage of air along the mutually contacting surfaces of the shaft 164 and member 218. However, in case of any leakage of air into the suction system along these surfaces such air will be drawn in through the openings 226 in the casing 160, and there will be substantially no tendency to suck oil from the bearings 167 to be drawn into the air passages.

Pipe 221 communicates at its inner end with a second nipple 230 which passes through an enlarged opening 231 in one of the plates 149 and is screwed into the column Q where it connects with a short side bore 232 and thence with a vertical bore 233, terminating in an annular groove 234, (see, particularly, Figure 18). At one point beneath the annular groove 234 the bearing plate 134 and the turn table casting J are formed with connecting vertical passages 235, which lead to a horizontal passage 236, connecting through the casing 237 with the interior of the automatic cut-off and controlled valves 238.

The above described structure forming the nozzle L, frame M and column Q constitute the disk holder assembly, of which there are ten mounted on the turn table J.

Shaft S extends downwardly through the outwardly extending portion 115 of the turn table J where it is journaled in ball bearings 240. Secured to the bottom of the portion 115 adjacent each of the shafts S is a downwardly extending bracket 242 formed with a tubular portion 243. A short vertical shaft 244 is journaled in the tubular portion 243 in ball bearings 144.

Shaft 244 is adapted to be coupled to and uncoupled from the shaft S by a cone clutch 245, consisting of an upper clutch member 248 keyed to the shaft S and normally pressed into engagement with the clutch member 246 by springs 249 interposed between the member 248 and a collar 250 secured to the shaft S, (see Figure 14).

Member 248 is moved out of clutching engage-

ment with the member 249 by a yoke 252 (Figure 14) pivoted at 253 in the bracket 252, and having at its outer edge a roller 255 adapted to ride up on a stationary cam 256 as the turn table J revolves. An elevation of the cam 256 with the rollers 255 of three successive grinding heads on the turn table is shown in Figure 15.

Stationary cam 256 is secured to a downwardly projecting flange 260 of a supporting plate 261 mounted on the brackets 71 shown in Figure 2 10 and a bracket 71', forming part of the supporting framework of the pick-up mechanism T, (see Figure 4).

At the lower end of shaft 244 is a pinion 264 which is driven from a larger gear wheel 265, 15 which, in turn, is driven from pinion 267 secured to the top of a vertical shaft 268 (see Figure 2), driven from the main drive shaft 79 by any suitable transmission, not shown but housed with a gear casing 270 supported from the base 69 of 20 the machine, (see Figure 2).

It will be apparent that during the period when the clutch 245 connects the shafts S and 244, operation of the gear 265 from the motor 75 serves to rotate the shaft S and operate the gearing R 25 which rotates the nozzle shaft 164 and the disk or lens held at the end of the nozzle. When, during the rotation of the turn table, the roller 253 rides up on the cam 256, shaft 244 is uncoupled from shaft S and rotation of the disk O stops. 30 This occurs as the disk O passes from beneath the grinding wheel F at approximately the position P1, in Figure 5, and the cam 256 is of such length as to hold the clutch uncoupled until the position P2 is reached. In the meantime the 35 disk, as previously stated, has been lifted off from the grinding wheel B, moved outwardly, discharged on to the carrier W, and a new disk O has been received from the pick-up mechanism.

The sleeve 136, which forms part of the supporting structure Q, mounted on the turn table J extends downwardly through a bearing opening 290, in a casting 291, which is secured to and rotatable with the turn table J as by bolts 292, which extend through the casting 291 and the outwardly 45 extending portion of the turn table. This casting is formed with a bearing opening 295, extending vertically through an outward extension 296 of the casting and mounted in this opening 295 and in an opening 295' in a downwardly extending casting 299 secured to the turn table J is a vertical shaft 297. Keyed to the downwardly projecting sleeve 136 is a pinion 298 which is adapted to be engaged and operated by a segment 303 secured to the shaft 297. Ten of these segments 55 300 are employed, as shown in Figure 20. Secured to the bottom of the shaft 297 is an arm 303 carrying at its outer end a roller 305, which rides in a cam slot 306 of a stationary cam guide 307, carried by the stationary plate 261. 60

The contour of the cam formed by the parts 307 is shown in Figure 20, and the relative positions of the segments 300, which operate the several pinions 298 on the sleeves 133 are shown.

The movement of the pinion 298, as effected by 65 the segment 300, determines the swing of the disk holder from one to another of the successive positions shown in Figure 5. It will be noted that from position P2 to P3, the swing of the disk holder is relatively slight, the cam slot over this 70 range of movement being but slightly eccentric to the axis of the wheel B.

The curvature of the cam slot, however, is sufficient to cause the disk holder to be swung inwardly until in position P1, it is substantially 75

radial to the axis of the wheel B. From this point on the cam roller 305 enters an outwardly inclined portion of the cam slot, indicated at 310, in Figures 3 and 20, which results in a considerable movement of the segment 300, thus rapidly swinging the disk holder through successive positions P12, P13, P14, and P15 to the discharging position P16. Then follows substantially a concentric portion 311 of the cam slot in which the disk holder remains substantially radial to the axis of wheel B. Then follows an inwardly inclined portion 313, which has the effect of rapidly turning the lens holder inward, as is indicated in positions P1 and P2 in Figure 5.

As previously stated, from position P11 to position P14,—that is, while the disk, after having been ground, is moved outwardly over the grinding surface C, it is lifted so as not to contact with this surface. This is accomplished by tilting the frame M about its pivotal support 147 by engagement of a lug 322 secured to the lower face of the cross bar 211 by a downwardly movable cam head 324 on a rod 325, which extends vertically through the cross piece 214 secured to the top of the projections 190 of the disk holder head structure Q.

The cam head 324 is normally held in elevated position by a spring 326 seated at one end in the bottom of a recess 327 in the cross piece 214 and pressing, at its upper end, against the lower edge 30 of the cap 328 screw threaded, or otherwise suitably secured to the top of the rod 325. A pin 329 projecting from the rod 325 into a vertical slot 339 in a cross piece 214 prevents rotation of the cam head 324.

The rod 325 is moved downward to tilt the frame M upwardly by engagement of the cap 328 with a cam 331 secured to the lower side of a bar 332 supported at one end from the top of an upright 336, forming part of the frame work of the pick up mechanism and secured at its opposite end to the cross bar 93.

Figure 3 shows one of the disk holder heads about to pass beneath the bar 332 and cam 331, thus effecting a tilting of the frame M, and a lifting of the disk O to a position above the grinding surfaces D and C.

As previously explained, suction for the disk holder nozzles is obtained through the flexible pipe 224 and thence through the bores in the structures Q and J, and through the cut-off and control valves 238.

The cut-off valve structure is shown in Figures 27, 31, and 32.

The casting 237 is secured to the outer edge of the turn table J by bolts 350 which pass through openings 351 in the ends of the casting. The upper portion of the casting 237 is formed with a chamber 352 closed at its upper end by a cap 353 and communicating at its bottom with a passage 354 which leads outward through the face of a cylindrical portion 355 of the control valve 356, (see Figure 31). Mounted to move up and down in the valve chamber 352 is a movable valve member 360 which is carried by a valve stem 361 that extends up through a central opening in the cap 353. The movable valve member 360 is a metal disk formed with cutaway portions 363 around its periphery so as to permit air to pass around the member 360 when this member is raised above the bottom of the chamber 352.

The valve member 360 is normally held in its raised position by a spring 365 which engages at one end a collar 366 on the stem 361 and at its other end the cap 353. The collar 365 is held

against upward movement by nuts 366' which may be adjusted to vary the tension of the spring 365.

An enlargement 368 on the stem 361 limits the upward motion of the valve member 360 under influence of the spring 365.

It will be understood that the air passages from the suction nozzles, including the passage 236, valve chamber 352, and passage 354, finally connect with a pump or other source of suction and that air is drawn through these passages from the disk holder nozzle. It will also be understood that there is a cut off valve and control valve for each of the disk holder heads, each serving to control the suction to its own disk holder.

The release of the disk which has been ground is accomplished by relieving the suction from the disk holder nozzle, thereby permitting the disk to drop on to the carrier W, as shown in Figure 5. From the position P15, at which the disk is discharged to the position P1, there is no suction applied to the disk holder until a new disk has been positioned by the pick-up mechanism against the seat 171 of the disk holder nozzle. Suction is then applied, which serves to hold this disk tightly against the seat. If, by any chance, the disk, which is placed at this time against the nozzle seat, is broken or otherwise defective so as to permit the passage of air into the nozzle, or if, during the process of grinding, the disk should become broken so as to allow entrance of air into the nozzle, there will be a considerable flow of air through the suction passages, including the passage 236 leading to the cut-off valve, through the chamber of the cut-off valve and around the valve disk 360 to the passage leading from the bottom of the valve chamber.

This flow of air through the valve will have the effect of forcing the valve disk 360 against the action of the spring 365 and moving this disk down to the bottom of the valve chamber 352, where it will be seated and effectively close the opening into the passage 354. The continued suction will hold the valve in its closed position until the suction is again relieved as the disk holder moves to its discharge position. The automatic cut-off, therefore, serves to prevent the leakage of air into the suction system when an attempt is made to hold a defective lens, and the defective lens, under such conditions, will drop from the holder.

The cylindrical portion 355 of the casting 237 forms a seat for a rotary circular disk valve member 370.

The rotary valve member 370 is held against the face of the seat 355 by a bolt 371, which extends through the seat 355, through the member 370 and thence through a triangular operating member 373, shown in Figures 30 and 34.

Nuts 374, at the outer end of the bolt 371, serve to hold the operating member 373 in position and a coil spring 376 pressing between the operating member 373 and the valve member 370 acts to maintain the member 370 in close facial engagement with the seat 355, the contacting surfaces being carefully ground to prevent leakage. The seat 355 is formed with an outlet passage 377 which communicates with the nipple 378 and the outlet pipe 379. The passages 354 and 377 open through the circular face of the seat 355 at diametrically opposite points, as shown in Figure 31, and the rotary valve member 370 is formed on its inner face with a curved groove or channel 380, which, in the position of this member shown in Figure 29, forms a communication between the passages 354 and 377.

On turning the valve member 370 in a clockwise direction from the position shown in Figure 29 to the position shown in Figure 30, this communication between the passages 354 and 377 is broken and the suction from the nozzle holder is therefore cut off.

Pipe 379 extends inwardly toward the hub 116 of the turntable and communicates through a nipple 382 with a short passage 383 in the outwardly extending portion 115 of the turntable casting. This passage, 383 communicates at its bottom with an annular groove, 384, this groove forming a common passage, to which the suction passages of all the disk holders lead. The groove 384 is closed at its bottom by a stationary plate 385 supported from the casting 38 by lugs 387, a portion of one of which is shown at the left of Figure 4.

One of these lugs, viz., that shown at the left of Figure 4 is formed with a central passage 389 which communicates at its upper end with an opening 390 in the plate 385, located immediately below the channel 384. Passage 389 communicates at its bottom with a passage 393 in the column casting 39, and this passage communicates with a pipe which leads to a suction pump, not shown.

For the purpose of operating the control valve so as to relieve the suction at the discharge position P16 and to apply the suction when the disk holder has reached the position P1 and is receiving a new disk, I provide two lugs, 400 and 401, rigidly secured to the outer edge of the stationary plate 261 shown in elevation in Figure 14 and in top plan view in Figure 33.

The lug 401, as shown in Figure 14, extends somewhat higher than lug 400, and is adapted to engage the inclined surface 403 of the control valve operating plate 373 to move the plate from the position shown in Figures 29 and 34 to the position shown in Figure 30, as the turn-table moves the disk holder to the position P16. This cuts off the suction from the disk holder nozzle and allows the finished disk to drop on to the carrier W.

Continued rotation of the turn-table carries the control valve and its operating plate 373 around until the inclined face 405 of the operating plate engages the stationary lug 400, this being the position of the disk holder indicated by P1 in Figure 5. Just previous to the movement of the disk holder into this position, the nozzle has received from the pick up mechanism a new disk, O, and upon operation of the valve operating plate 373 by the lug 400, the control valve is moved again to the position shown in Figure 29 where the slot or groove 380 forms a communication between the passages 354 and 377 and permits suction to be again applied to the nozzle, thus firmly seating the disk O in position on the nozzle to be carried through the grinding operations.

The pick up mechanism

The pick up mechanism T comprises a base 450, which forms an extension of the base 69 of the grinding machine; base 450 supports the uprights 336, 336', which are connected at their tops by a cross bar 451 formed with a vertical bearing opening 452, which receives the upper end of a shaft 454, to which is secured a rotating supporting plate, or spider 455, in which are mounted, at equally spaced points near its periphery, a series of disk holder cages 456, each of which is adapted to hold a stack of disks or lenses 457 which are to be delivered to the grinding machine for bevel-

ing. Shaft 454 is journaled at its lower end in the bearing 460, formed in the top of a gear casing 461, carried by the base 450.

The gear casing 461 contains a Geneva movement, comprising a gear or wheel 463 adapted to be engaged periodically by the pin 464 eccentrically mounted on a vertical stub shaft 465, (see Figure 10) thus rotating the wheel 463 step by step in a manner well known in the art.

Stub shaft 465 carries at its upper end a beveled gear 467 which is driven from a gear 468 secured to the outer end of shaft 108. It will thus be clear that vertical shaft 454 and the disk carrying plate 455 are intermittently rotated from a change speed gearing 80, through the shaft 100, gears 101, 15 102, beveled gears 104, 105, shaft 108, beveled gears 468, 467, stub shaft 465, and shaft 454.

The holders or cages 456 for the stacked disks each comprise four upwardly extending spaced fingers 470 joined at their bottom by a hub or base portion 471, from which extends a downwardly projecting angular pin 472, which is received in an angular socket or recess 473 formed in the top of an upright rod 474. The rod 474 is preferably angular in section and is received in angular opening 475 in the plate 455. The rod 474 extends downwardly through an opening 478 in the supporting plate 479, secured to the vertical shaft 454 and is normally held in the position shown in Figure 14 by engagement of the shoulder 479' on the rod 474, with the plate 479 at the tap of the opening 478.

In all I provide on the plate 455 ten lens holding cages 456 arranged around the periphery of the plate and ten rods 474. Each of the rods 474 terminates at 480 and at one position of each rod, as it is carried intermittently around the axis of the shaft 454 by the intermittent rotation of the shaft, the lower end 480 of the rod is adapted to be engaged by a rod 482, and the rod 474 and the cage 456 lifted thereby to a position shown diagrammatically in Figure 22, in which the uppermost disk of the stack 457 is brought into contact with the pick-up disk holder nozzle 488, to be lifted by the nozzle to the nozzle L of the grinding machine.

Rod 482 slides in a tube 489 and is biased to its raised position by a spring 490 secured at one end to a pin 491 projecting outwardly from the rod 482 through a slot 492 and secured at the other end to a pin 493 projecting from the upper end of the tube (see, particularly, Figure 22).

Rod 482 is moved to its lowermost position by an arm 496 pivoted at 498 on the upright 336 and adapted to be moved downwardly by a cam 500 which engages a roller 501 carried by a pin 502 projecting from the arm 496. The arm 496 engages a roller 503 carried by the end of the pin 491 opposite to that to which the spring 490 is attached.

In operation, the Geneva movement in the casing 461 operates to turn the shaft 454 so as to bring the disk holding cages successively under the pick-up nozzle 488, the shaft 454 remaining stationary at this point until a disk has been picked up by the pick-up nozzle from the stack held by the cage.

In the act of picking up the top disk of the stack the inwardly inclined face 510 of the cam 500 moves over the roller 501 on the arm 496, thus permitting the arm 496 to be swung upward under the influence of the spring 490 which also serves to move the rod 482 into contact with the bottom of the rod 474 and to raise the rod 474 and the disk holder cage upward until the top disk of the

stack contacts with the pick-up nozzle. Inasmuch as the cage is secured by the action of the spring 490 the contact of the top disk with the pick-up nozzle is a yielding one, thus avoiding 5 injury to the disk.

At this point in the operation suction is applied to the pick-up nozzle X which serves to hold the top disk of the stack to the nozzle and continued rotation of the cam 500 depresses the arm 496 10 and the rod 492 thus permitting the cage 456 to drop, leaving the top disk held by the pick-up nozzle holder.

In Figure 35 I show a sectional view of the pick-up nozzle X. This nozzle comprises a tube 512, 15 screw-threaded into a tubular extension formed on the hub portion 514 carried by a transverse shaft 515 journaled in the top of the uprights 336 and 336'.

The tube 512 is externally screw-threaded and 20 is adapted to be screwed into or out of the projecting portion 513 by a suitable tool engaging in opening 517 in the tube 512 and held securely in its adjusted position by a lock nut 518. The outer end of the pick-up nozzle X carries a rubber ring 25 520, which forms at its outer end a cushion seat for the disk.

The adjustment of the pick-up nozzle is important in accurately positioning the nozzle for proper engagement with the disk holder nozzle X 30 of the grinding machine during the operation of transferring the disk from one nozzle to the other.

The hub 514 of the pick-up nozzle is adjustably secured to the shaft 515, and may be held in its 35 adjusted position by a clamping screw 521. It will of course be understood that the hub 514 will be suitably packed to prevent leakage of air into the suction passage.

The pick-up nozzle X at the time it is receiving 40 a disk from the stack of disks 457 extends downwardly from the shaft 515 and subsequently is swung upwardly to the position shown in Figure 16 for transferring the disk to the disk holder L of the grinding machine. This swinging motion is accomplished by rotating the shaft 515 by means of a segment 525 which engages a 45 pinion 526 secured to the shaft 515. (See Figures 4 and 21.)

Segment 525 is secured to a transverse shaft 528 journaled in uprights 336 and 336' and 50 having secured thereto at one end an arm 529 to which is pivotally connected a link 530 which extends downwardly, and in turn is pivotally connected to a second arm 531 secured to a short transverse shaft 532 pivotally mounted in the bracket 71'.

Shaft 532 carries a cam arm 533, which engages a cam slot 534 of a cam 535 secured to the shaft 108. (See Figure 1.)

From the above it will be seen that the rotation 60 of the shaft 108, the cam arm 533 will be swung alternately in one direction and the other, and this through the shaft 532, arm 531, length 530, arm 529, will turn the shaft 528 and the segment 525, thereby rotating the gear 526 and shaft 515, thus swinging the pick-up nozzle X toward the grinding machine nozzle and downwardly 65 toward the disk-holder cage 456.

The shaft 515, which carries the pick-up nozzle, is movable longitudinally in its bearings and is 70 biased to the position shown in Figure 21 by a coiled spring 540 which surrounds the shaft and presses at one end against the upright 336' and at the other end against an arm 542 adjustably secured by a bolt 543 to the shaft 515. The arm 542 is adapted to be engaged by an extension 75

544 formed at the outer end of one of the side plates 149 of the disk holder L, as this disk holder swings about the axis Q' of the vertical sleeve 136, thus causing the pick-up and grinding machine disk holders L and X to move with one another for a short period of time during the transfer of the disk from the pick-up disk holder to the grinding machine holder. During this short interval of time the pick-up disk holder and the grinding machine holder are in substantial alignment with the disk between them, in the relative positions shown in Figure 16, and during this short interval, when the grinding machine disk holder is swinging about the axis Q' and the pick-up disk holder is being carried with it, the suction which holds the disk to the pick-up disk holder is released and the suction of the grinding machine disk-holder is applied, and in this manner the disk, which was previously held by the pick-up disk holder, is now transferred and held 20 by the grinding machine disk holder. Preferably the suction is applied to the holder L a moment before it is cut off from nozzle X.

Pinion 526 and segment 525 are sufficiently wide to permit their meshing throughout the 25 entire range of longitudinal movement of the shaft 515.

A comparison of Figures 23 to 26, particularly in connection with Figure 5, will show the movements of the pick-up and grinding machine disk 30 holders relative to one another during the operation of transferring the disk from the pick-up to the grinding machine.

In Figure 23 the grinding machine disk holder L is shown in a position which it occupies prior to 35 engagement with the pick-up nozzle, this position being one between the position P16 and P1 in Figure 5. The pick-up nozzle has received the lens O from a stack of lenses and has been swung slightly upward toward the left, in a direction toward the holder L.

Figure 24 shows the position of the holders a moment later, when the grinding machine holder nozzle has moved into contact with the disk. The arm 542 on the shaft 515 of the pick-up mechanism has swung upward with the pick-up nozzle X and the projection 544, which is preferably rubber-tipped at 560 to ease the contact with the arm 542, is now in engagement with the side of this arm, so that further swinging movement of 50 the disk holder L moves the pick-up disk holder nozzle longitudinally with the shaft 515 against the action of the spring 540. The two disk holders move together to the positions shown in Figure 25, in which both nozzles lie in a plane 55 radial to the main axis of the grinding wheel B, which is the position P1 of Figure 5. At this point suction is applied to the grinding machine disk-holder nozzle, and released from the pick-up nozzle, thus causing the disk now to be held 60 by the grinding machine nozzle.

By reference to Figure 5, it will be seen that from position P1 the grinding machine disk-holder swings inward on its axis Q' so as to bring the disk O toward the grinding wheel B. An 65 initial stage of this inward swinging movement is shown in Figure 26, which shows the grinding machine and pick-up disk holders about to separate. In this motion of separation the grinding machine disk-holder swings in a counter clockwise direction and permits the spring 540 to move the shaft 515 and the pick-up holder gradually back to its initial position, and after the separation the grinding machine disk-holder continues its movement, as illustrated in Figure 5, 70 75 75

while the pick-up disk holder, with the shaft 515, slides back under the influence of the spring 549, and the pick-up nozzle swings back to a vertical position preparatory to receiving the new disk 5 to be delivered to the next grinding machine disk holder, as this disk holder moves toward position P1 of Figure 5.

During the movements illustrated in Figures 24 to 26, the holder plate 455 has been rotated one 10 step by the Geneva movement and brought another disk-holder cage 456 into position to be raised by the rod 480 to deliver the top disk to the pick-up nozzle.

In Figures 35 to 38 I show diagrammatically 15 the air system for controlling the suction to the pick-up nozzle, together with the means for operating the control valve of this system from the shaft 108.

Referring to Figure 35, the bore in the tube 20 512 of the pick-up nozzle communicates through a short passage 570 with a longitudinal central passage 571, which extends toward the right to the opening 572, through the wall of the shaft.

The shaft 515 is formed near this end with a 25 shoulder 573 against which is driven a collar 574, and between the collar 574 and a hub 575, surrounding the shaft, is a fibre washer 576. The longitudinal opening 571 in the shaft 515 is formed with an enlarged outer end 578, into which 30 is driven a pin 579 which fills the opening and closes the outer end of the longitudinal passage.

This pin carries a washer 580 at its outer end, which is secured in place by a nut 581. Enclosing the outer end of the pin 579 is a cap 582, which is 35 formed with flanges 583 through which extend screws 584 that secure the cap 582 to a metal washer 585. Interposed between the washer 585 and the outer end of the hub 575 is a fiber washer 586.

Reference character 590 represents a helical 40 spring surrounding the pin 579 and pressing at one end against the washer 580 and at the other end against the metal washer 585, this spring serving to press the cap end connected metal 45 washer 585 toward the left, thus pressing the metal washer 585 against the fibre washer 586, and the fibre washer 586 against the outer end of the hub 575 to provide a proper sealing contact against the admission of air to the suction 50 system. This spring, as will be seen from Figure 35, also serves to press the hub 575 against the washer 576. The hub 575 is provided with forked projections 591 which embrace an outwardly extending guide pin 593 secured to the upright 55 336, thus preventing turning movement of the hub 575 as the shaft rotates and at the same time permitting longitudinal movement of the hub as the shaft 515 slides in its bearings.

The hub 575 is formed with an internal annular recess or groove 600, which communicates at one point through the opening 601 with a flexible tube 602 which leads to the cut off and control valve structure 603 secured to one of the brackets 77 by bolts 604. (See Figure 21).

The cut-off and control valve structure for the 60 pick-up is very similar to those employed for the several disk holder assemblies shown in detail in Figures 27 to 32. It comprises a casting 605 having a cut-off valve chamber 607, in which 65 operates the cut-off valve head 608 in substantially the same way as the cut-off valve head or disk 360 of Figure 32.

As the construction of the parts of the cut-off valve shown in Figure 36 is quite similar to that 70 shown in Figure 32, I have employed the same

reference characters with the addition of a prime (') for a number of the corresponding parts in Figure 36.

Similarly the control valve shown in Figure 37 is quite similar to that for the disk holder assemblies in Figure 31, and I have also employed the same reference characters in Figure 37, with the addition of the "prime" (') indication.

The shaft 371' in Figure 37 has secured to its outer end an arm 620 to which is pivotally secured a link 609 pivotally connected to an upwardly projecting arm 610 secured to a shaft 611 supported from the base of the machine. Shaft 611 carries a cam arm 612, which carries at its outer end a roller 613 which operates in the cam 15 slot 614 of a cam 615 secured to the shaft 108.

It will thus be seen that rotation of the cam 615 causes a rocking of the arm 612 and shaft 611, and a corresponding rocking of the arm 610, and through the connecting link 609 and the actuating arm or head 620 causes the rotary valve plate 370' to alternately make and break communication by means of the groove 388' between the passages 354' and 377'.

Passage 354', as is plain from Figures 35, 36, 25 and 37, is in communication with the hub 575 on the hollow shaft 515 and the nozzle tube 512.

Passage 377' leads to a nipple 616, thence to a pipe 616, which leads to the suction pump, not shown.

30

The cam slot 614 on the cam 615 is so formed that the control valve is actuated to apply the suction to the pick-up nozzle while the cage 456 is in raised position and nozzle in contact with the top disk of stack of disks held by the cage, 35 and to release the suction when the pick-up nozzle is in the position shown in Figures 25 and 16 as the disk is being transferred to the grinding machine nozzle.

It will be seen that the machine described 40 is entirely automatic in operation, it being merely necessary for the operator to supply the several cages 456 with disks to be ground. The construction of these cages is such that disks may be readily inserted or removed, if necessary, the 45 space between the prongs 470 giving ample room for the fingers of the operator in inserting or removing the disks.

The various adjustments of the machine above 50 described permit the cutting of the disks to exact diameter so that, if desired, the disks delivered by the machine may be of the same diameter to within a fraction of a millimeter. It also permits disks of different diameters to be handled with similar advantage of adjustment for producing 55 a uniform product.

The pick-up mechanism, while shown as means for transferring the disk to be ground from a stack or other group of disks may, if desired, be employed for transferring a disk from one operation to another on the same machine in case it was desired to have the disk operated upon by a plurality of stones.

In Figures 41 and 42 I show diagrammatically 65 a means for transferring a disk from one grinding mechanism to another. While the grinding mechanisms disclosed are of a type similar to that shown in other figures of the drawings, it will be understood that I am not limited to any particular type of mechanism. The grinding 70 mechanisms 700, shown at the left of Figures 41 and 42, may perform a series of grinding operations, and that at the right a series of polishing operations. Between the two mechanisms, A and A', is a transfer nozzle 704 which is adapted to 75

swing about a horizontal axis so as to receive a disk from a nozzle of one of the mechanisms, and deliver it to a nozzle of the other mechanism.

The nozzle 784 is secured to a shaft 706, which is 5 is slidable in its bearings in a manner similar to the shaft 545 of the pick-up mechanism T. Shaft 706 may conveniently be rotated by a gear 739 which meshes with a segment 710 secured to the shaft 706. Gear 709 is secured to a second 10 shaft 711 which, in turn, is rotated from a vertical shaft 712 by bevel gears 713. It will be understood that these gears are actuated and timed in proper relation to the nozzle holders of the two mechanisms, A and A', to receive the 15 disk or other article from one of the nozzles and then swing into position to deliver the disk to an adjacent nozzle of the other mechanism. Also, it will be understood that suction control means is provided which applies suction to the transfer nozzle as it receives a disk from the nozzle of one mechanism and releases the suction from the latter nozzle, and subsequently, after the transfer nozzle has been swung to position to cooperate with a nozzle of the other mechanism, suction is applied to the last named nozzle and released from the transfer nozzle.

This application is a continuation in part of my application, Serial Number 388,883, filed August 28, 1929.

30 I claim:

1. In a grinding device, a rotary grinding member having at one side thereof concentric grinding and polishing surfaces, a container for disks to be ground, a disk holder, means for automatically transferring disks from said container to said holder, and means for moving said holder so as to bring the edge of a disk successively into contact with said grinding and polishing surfaces.

40 2. In a grinding device, a rotary grinding member having at one side thereof concentric grinding and polishing surfaces, a container for disks to be ground, a disk holder, means for automatically transferring disks from said container to said holder, means for moving said holder so as to bring the edge of a disk successively into contact with said grinding and polishing surfaces, and means for automatically moving said holder away from said grinding member and discharging the disk held thereby.

45 3. The combination of two grinding mechanisms, each having a grinding member and a disk holder adapted to hold a disk in contact with said member, of means for automatically transferring a disk from the holder of one mechanism to the holder of the other mechanism.

50 4. In a machine for grinding the edges of glass disks, a rotary grinding member having a substantially flat annular grinding surface and an annular polishing surface concentric with the grinding surface, a disk holder having means for rotating the disk held thereby about its own axis, pivotal means for supporting said disk holder with the disk in contact with said grinding surface, means for swinging said holder and disk across said grinding surface and means for returning said disk without contact with said grinding surfaces.

55 5. A machine for grinding the edges of disks, a rotary grinding member having a substantially flat outer grinding surface and a substantially flat inner polishing surface, a disk holder adapted to hold a disk with its edge in contact with said surface and having means for rotating said disk about its own axis, means for swinging said hold-

er so as to move said disk across and in cooperative engagement with said outer and inner surfaces and means for returning said disk without contact with said surfaces.

6. A machine for grinding the edges of disks, 5 a rotary grinding wheel having a substantially flat outer grinding surface and a substantially flat inner polishing surface, a disk holder adapted to hold a disk with its edge in contact with said surface and having means for rotating 10 said disk about its own axis, and means for swinging said holder so as to move said disk across, and in operative engagement with, said outer and inner surfaces and for subsequently lifting said disk from operative engagement with 15 said wheel, moving it beyond the outer edge of said wheel and releasing said disk.

7. In a grinding machine, a rotary grinding member having at one side concentric annular grinding surfaces formed of different materials, 20 means for holding a disk, to be ground, in contact with one of said surfaces, and moving said disk subsequently into contact with the other of said surfaces, means for adjusting said rotary member longitudinally of its axis to compensate 25 for wear of both surfaces, and means for adjusting relative to one another said grinding surfaces in directions along their axis to compensate for differences of wear in said surfaces.

8. Means for beveling, and cutting a disk at 30 its edge to reduce it to a predetermined diameter, said means comprising two grinding wheels arranged face to face and having opposed grinding surfaces at their adjacent sides, means for passing a disk along said surfaces between said 35 wheels, and successively in contact with the grinding surfaces of the wheels.

9. Means for beveling, and cutting a disk at its edge to reduce it to a predetermined diameter, 40 said means comprising two grinding wheels arranged face to face and having opposed grinding surfaces at their adjacent sides, means for passing a disk along said surfaces between said wheels, and successively in contact with the grinding surfaces of the wheels, and means for 45 adjusting the distance apart of said wheels.

10. Means for beveling, and cutting a disk at its edge to reduce it to a predetermined diameter, said means comprising two grinding wheels arranged face to face with grinding surfaces on 50 their adjacent faces, means for passing a disk along said surfaces between said wheels and in contact successively with the grinding surfaces of the two wheels, biasing means for yieldingly pressing said disk against the first surface and 55 fixed means for holding said disk against the second surface.

11. A grinding member mounted to rotate in a horizontal plane and having an upper grinding surface, a turn table rotatable about the axis of 60 said member, a plurality of disk holders mounted on said turn table at points around the periphery of said member, and means for swinging said holders over the top of said surface to cause the disks held thereby successively to engage and 65 disengage said grinding surface.

12. A grinding member mounted to rotate in a horizontal plane and having an upper grinding surface, a support near the periphery of said member, a plurality of disk holder assemblies 70 arranged around said member and each pivotally mounted on said support at a point substantially level with said grinding surface, each of said holders comprising a disc holding casing whose axis coincides with the axis of the disk and each 75

- of said holders being adapted to hold a disc at an incline to and with its edge in contact with said surface and said axis and said pivotal point being arranged along one vertical plane.
5. 13. A grinding member mounted to rotate in a horizontal plane and having an upper grinding surface, a support near the periphery of said member, a plurality of disk holder assemblies arranged around said member and each pivotally mounted on said support at a point substantially level with said grinding surface, each of said holders comprising a disk holding casing whose axis coincides with the axis of the disc and each of said holders being adapted to move by gravity a disk at an incline to and with its edge in contact with said surface, and said axis and said pivotal point being arranged along one vertical plane.
10. 14. A rotary grinding member having a flat grinding surface, a support adjacent the periphery of said member, a plurality of disk holder assemblies arranged around said member, and each pivotally mounted on said support at a point substantially in the plane of said grinding surface, each of said holders comprising a disk holding casing whose axis coincides with the axis of the disk and each of said holders being adapted to hold a disk at an incline to and with its edge in contact with said surface, and said axis and said pivotal point being arranged along a plane at approximately right angles to said grinding surface.
15. 15. A grinding machine having a rotary grinding member, a turn-table rotatable about the axis of said member past a receiving station and a discharge station, a disk holder mounted on said turn table, cam actuated means for causing said holder to move a disk into and out of contact with said surface, a pick up mechanism at said receiving station adapted to deliver a disk to said holder as it passes said receiving station and means for automatically discharging the disk as said holder passes said discharge station.
20. 16. In an apparatus for transferring a disk from one apparatus to another, each including a suction holder nozzle, means for receiving the disk by one of said nozzles, means for moving said nozzles relatively to one another to a position in which said disk is held between said nozzles, means for releasing the suction from said one nozzle and applying it to the other nozzle, and means for separating said nozzles.
25. 17. In a device of the character described, a swinging nozzle having a disk holding seat, a second nozzle having a disk holding seat mounted to swing in a plane at an angle to the plane of movement of said first nozzle, means for swinging said nozzles so as to bring them into alignment with their seats closely adjacent to one another, separate means connected to the respective nozzles and adapted mutually to engage one another to cause one of the nozzles to move the other nozzle with it during the period when they are in substantial alignment and a yielding support for said other nozzle designed to permit such movement.
30. 18. In a pick-up mechanism, a rotary support, containers for stacks of disks mounted on said support, a suction nozzle pivotally mounted above said support, means for moving said support so as to bring said containers successively beneath said nozzle, means for swinging said nozzle to a position in alignment with the stack beneath the nozzle, yielding means for raising the container of said stack until the top disk of the stack is in contact with the nozzle, means for applying suction to the nozzle for retaining the top disk, and means for lowering the container.
35. 19. A disk holder nozzle comprising a rotary hollow shaft formed with a disk holding seat at one end, a casing surrounding said shaft and having a bearing for said shaft adjacent one end, said shaft being formed with an external annular groove located inside said casing and communicating with the interior of said shaft, a sleeve 5 surrounding said groove and fitting said shaft at opposite sides of said groove, said sleeve terminating short of said bearing and said casing being formed with an opening between said sleeve and bearing, and means for applying suction to said 10 groove.
40. 20. A rotary grinding wheel having a grinding surface at one side thereof, a support adjacent said wheel, a member carried by said support and adapted to rotate during grinding in a plane 20 through the axis of said wheel, a disk holder pivotally mounted on said member at a point substantially in the plane of the grinding surface and adapted to swing in a plane substantially parallel to the axis of said wheel, said holder having a disk holding seat positioned eccentric to the axis of said member, whereby on rotation of said member the disk is swung over said grinding surface and on rotation of said holder about its own pivoted axis the disk is moved normal to the 25 grinding surface, and an adjustable stop to limit the movement of the disk in a direction toward said surface.
45. 21. A machine having a grinding wheel with a flat grinding surface, means for holding an object to be ground against said surface, means for rotating said object and moving the same in a direction toward said surface, means for arresting said movement when said object has been ground to a predetermined diameter, a screw 35 threaded shaft connected with said wheel, a source of power for turning said wheel and means for slowly advancing said shaft and wheel to compensate for wear of said surface, said means comprising a rotating element engaging the screw 40 threads of said shaft, a second element moved slowly by said source of power and a step by step operating connection between said first and second elements.
50. 22. A machine having a grinding wheel with a flat grinding surface, means for holding an object to be ground, against said surface, means for rotating said object and moving the same in a direction toward said surface, means for arresting said movement when said object has been 55 ground to a predetermined diameter, a shaft on which said wheel is mounted, means for advancing said shaft and wheel during the grinding operation to compensate for wear of said grinding surface, said means including a source of power and a step by step operating connection between said source and said shaft.
55. 23. A machine having a grinding wheel with a flat grinding surface, a turn table surrounding said wheel, a plurality of disk holder assemblies supported by said turntable, and each adapted to hold a disk in contact with said surface, a source of power for slowly turning said turn table, means for rotating said disk and moving the same in a direction toward said surface, 60 means for arresting said movement when said disc has been ground to a predetermined diameter, and means for advancing said wheel during the grinding operation to compensate for wear of said surface, said means comprising an oper- 65
70. 75.

ating connection between said turntable and wheel.

24. In a grinding machine, a grinding wheel a plurality of suction nozzles for holding disks to be ground against said wheel, a source of suction, means forming separate air passages between said source and the respective nozzles, and a valve in each of said passages operable upon a predetermined leakage of air through its respective nozzle for closing communication between said nozzle and source.

25. A transferring means for glass disks comprising a pair of suction nozzles movable concurrently in separate paths during small portions of which paths the nozzles are in alignment and closely adjacent to one another, a source of suction, and controlling means for applying suction to one nozzle for receiving and holding a disk until said one nozzle is moved to its position in alignment with and adjacent to the other nozzle, and thereupon releasing the suction from said one nozzle and applying suction to the other nozzle whereby the disk is transferred from one nozzle to the other.

26. A transferring means for glass disks comprising a pair of suction nozzles movable concurrently in separate paths during small portions

of which paths the nozzles are in alignment and closely adjacent to one another, a source of suction, controlling means for applying suction to one nozzle for receiving and holding a disk until said one nozzle is moved to its position in alignment with and adjacent to the other nozzle, and thereupon releasing the suction from said one nozzle and applying suction to the other nozzle whereby the disk is transferred from one nozzle to the other, and an operating connection between said nozzles, whereby one of said nozzles is moved by the other while the nozzles are adjacent.

27. The method of grinding the edge of a glass disk by means of a grinding wheel having a flat annular grinding surface, without the formation of shoulders on the disk or wheel, which method consists in rotating the wheel and disk about their respective axes and moving said disk into contact with the surface at one edge of said surface, thence across said surface and off said surface from the opposite edge thereof, and pressing said disk against said surface with a pressure which is diminished to substantially zero as the disk passes off from said surface.

25

CHARLES V. WALTER.
